PROCESS FOR THE TREATMENT OF HYDROCARBON OIL

Filed Dec. 29, 1934

UNITED STATES PATENT OFFICE

2,099,919

PROCESS FOR THE TREATMENT OF HYDROCARBON OIL

Maurice H. Arveson, Highland, Ind., assignor to Standard Oil Company, Chicago, Ill., a corporation of Indiana

Application December 29, 1934, Serial No. 759,620

10 Claims. (Cl. 196—49)

This invention relates to processes for the treatment of hydrocarbon oil and pertains more particularly to processes for producing gasoline or other relatively light distillate from heavy hydrocarbon oil such as crude petroleum oil, reduced crude or the like.

It has been proposed heretofore to subject crude petroleum oil to fractional distillation to form a plurality of condensate cuts of different boiling ranges, then separately to crack these condensates in individual cracking zones under conditions best adapted for the conversion of each, then to combine the cracked products in a common vapor separating and fractionating zone wherein a further separation of the vapors, to give a plurality of condensates of different boiling ranges, is obtained; these last-mentioned condensates then being subjected to cracking in separate cracking zones under optimum cracking conditions and the resulting cracked products being combined for further separation and fractionation in the manner already described. In accordance with such prior proposals, the reduced crude resulting from the initial distilling step has either been withdrawn from the process or subjected to an entirely separate single-stage cracking operation.

In accordance with my invention I provide an improved process whereby the fresh charging stock, such as crude oil, is subjected to an initial distillation step wherein it is separated into a plurality of condensate cuts of different boiling point ranges, which may include an overhead condensate of the boiling range desired for the final products, and a reduced crude residue. Each one of these condensate cuts, except that one which is of the desired boiling range for the final product, is passed once through an individual cracking zone wherein it is raised to a cracking temperature and subjected to conversion, all of the resulting cracked products being introduced into a common vapor separating and fractionating system, wherein a further separation into a plurality of condensates, including an overhead condensate having the final desired boiling characteristics, and a residue, occurs. Meanwhile, the residue from the initial distilling operation is subjected to a cracking operation and is introduced into the common vapor separating and fractionating system mentioned.

The cracking of the reduced crude residue may be carried out either by passing the reduced crude through a heating coil in a conventional furnace, wherein it is raised to a cracking temperature and subjected to the desired degree of

conversion, or by combining it with one of the stream of hot cracked condensate and then introducing the mixture into the separating and fractionating system.

By this procedure, the reduced crude may either be cracked entirely by aid of heat derived from the furnace coil, or by contact with the highly heated cracked condensate, prior to the introduction of the mixture into the separating and fractionating apparatus. Or the heating may be carried out first by passage of the oil through the heating coil in the furnace and then by contact with the highly heated cracked condensate. Additional cracking by contact with the highly heated cracked condensate may be insured by the provision of a soaking drum or reaction chamber in which the mixture of cracked condensate and reduced crude is digested for a sufficient length of time to bring about the desired degree of conversion.

The commingled cracked products are separated, in the vapor separating and fractionating apparatus, into a plurality of condensate cuts of different boiling ranges including an overhead product falling in the boiling range of the final desired product, and a liquid residue. Condensates so obtained, except gasoline, are separately cracked by being passed once through individual cracking zones and all of the resulting cracked products are introduced into a second vapor separating and fractionating apparatus. Simultaneously the partially cracked liquid residue from the first separating operation is passed through a separate cracking coil and is then introduced into the second vapor separating apparatus, either directly or after having been commingled with highly heated cracked condensate from one of the last-mentioned cracking operations, this commingling preferably taking place in a soaking drum wherein a sufficient time of reaction is provided to insure the necessary cracking of the reduced crude. Here again part of the cracking may be carried out in the cracking coil and the rest by direct contact of the reduced crude with the highly heated cracked condensate in the soaking drum.

If the liquid residue withdrawn from the first separating zone has too great coke-forming tendencies for efficient cracking in a furnace coil as mentioned, the residue may be passed instead of through the coil, directly from the first separating zone into combination with one of the highly heated cracked condensate streams, in a soaking drum as already described. In this case all of the cracking of the residue would be

- carried out by heat derived through the direct contact thereof with the highly heated cracked condensate. According to any one of these alternative methods the resulting cracked residue 5 finds its way into the second separating zone wherein a plurality of condensate cuts of different boiling point ranges and a liquid residue may be isolated just as described in connection with the second separating and fractionating 10 step. Usually three successive cracking steps will be found sufficient and usually it will be desirable to crack the reduced crude in a directly fired coil to effect the first cracking step and then to carry out the next two cracking 15 steps on the residues by direct contact of the residues with highly heated cracked condensates, or by this procedure coupled with preliminary heating and perhaps partial cracking of the residues in individually directly fired coils.
- 20 The vapors from the final cracking step of the series may be fractionated to give a final desired light distillate and one or more reflux condensates which may be withdrawn for sale as distillate fuel oil, or for separate cracking. The 25 liquid residue from the final cracking stage of the series may be subjected to a flashing operation in a separate tar flasher and the resulting distillate may be passed through one of the cracking zones mentioned, preferably through 30 one of the zones treating liquid residue.
- Where an intermediate condensate is cracked and used as a heat carrier for aiding in the conversion of liquid residue, the condensate may be of a relatively light character so that it can be 35 heated to a sufficiently high temperature to carry out the necessary cracking, this light character and high temperature being particularly desirable in the latter stages of the process. The various cracking coils may be located in separate 40 furnaces or in a common furnace or furnaces, the latter being usually preferable from an initial cost viewpoint. The cracking conditions maintained in the various cracking zones may be selected, in accordance with the teachings of the 45 prior art for the cracking of stocks of like nature. However, as a general rule it is preferable to use relatively high-temperature, short-time cracking conditions for the treatment of the condensate stocks.
- 50 The above-mentioned and further objects and advantages of my invention and the manner of attaining them will be more fully explained in the following description taken in conjunction with the accompanying drawing.
- 55 The single figure of the drawing represents diagrammatically an oil cracking system embodying my invention.
- Referring more particularly to the drawing, reference numeral 1 indicates a crude flash tower 60 and numerals 2, 3 and 4 indicate combination evaporating and fractionating towers. Five (5), 6, 7, 7', 8, 9, 9', 10 and 21, refer to separate cracking coils of the directly-fired type which may be located in separate furnaces or in a common 65 furnace or furnaces.
- Fresh relatively heavy charging stock, such as 33° A. P. I. gravity Mid-continent crude oil, partially reduced crude, or the like, having light as well as heavy constituents, is introduced into 70 tower 1 through pipe 11 by action of pump 12, after having been suitably preheated in any well known manner, either by indirect heat exchange with some of the cracked products in succeeding steps of the process, or by passage through a directly-fired coil, to a temperature sufficient to

promote the desired degree of distillation. In the tower 1 the introduced oil separates into vapors and liquid residue, the former passing upwardly through the tower and the latter collecting in the base thereof, in the usual manner. A 5 plurality of intermediate condensate cuts are collected, for example two as shown, by aid of trap-out trays 13 and 14. The condensate collected on the former may be a clean gas oil and that collected on the latter may be a heavy 10 naphtha, which it is desired to reform. The gas oil is withdrawn from tray 13 through pipe 15 and is forced by pump 16 through the heating coil 5 wherein it is raised to a cracking temperature and subjected to conversion. The resulting cracked products pass through the transfer line 17 into the evaporator section 18 of combination tower 2, preferably after having passed through a soaking drum 19. This drum may be by-passed if desired. At the same time the 20 heavy naphtha is withdrawn from trap-out tray 14 through pipe 19' and is forced by pump 20 through the reforming coil 21 wherein it is raised to a relatively high cracking temperature sufficient to cause the reformation thereof to higher 25 anti-knock gasoline constituents. The reformed products travel through transfer line 22 into the evaporator section 18 in mixture with the other cracked products.

Simultaneously liquid residue is withdrawn 30 from the base of the crude flash tower through conduit 23 and is forced by pump 24 through the heating coil 6 wherein it is raised to a cracking temperature and subjected to a viscosity-breaking 35 operation, under conditions sufficiently mild to prevent deleterious coke deposition in the heating coil. The resulting cracked products are then introduced into the evaporator section 18, preferably directly through the transfer line 25, but alternatively through cross-over line 26 into the 40 soaking drum 19 wherein additional cracking thereof takes place, the resulting vis-broken or moderately cracked reduced crude finally 45 commingling with the other cracked products in the evaporator section 18. Valves 26' and 28 are inserted in the several transfer lines for pressure control purposes.

In the evaporator section 18 the cracked products separate into vapors and liquid residue, the former passing upwardly through the fractionator section 29 of the combination tower and therein undergoing fractional condensation, while the liquid residue collects in the base of evaporator section 18. A plurality of condensate fractions of different boiling point ranges are 50 collected in the fractionating section, for example two in number, these being collected by trap-out trays 30 and 31. The condensate collected on the first-mentioned tray 30 may be a relatively light product such as light gas oil, kerosene, or 55 heavy naphtha, or a mixture of these, while that collected on the next lower tray 31 may be a clean gas oil condensate of somewhat lower A. P. I. gravity, being in the nature, however, of a clean cracking stock.

The condensate is withdrawn from tray 30 65 through conduit 33, having pump 34, and is forced through the heating coil 7 wherein it is raised to a relatively high cracking temperature and subjected to conversion, the resulting cracked 70 products being introduced into the evaporator section 35 of combination tower 3, through line 36. At the same time condensate is withdrawn from trap-out tray 31 by way of conduit 36', having pump 37, and is forced through the heating 75

coil 1' wherein it is raised to a relatively high cracking temperature and subjected to conversion, the resulting cracked products passing into the evaporator section 35 by way of pipe 38, preferably after having passed through soaking drum 39.

While these actions are taking place, liquid residue is withdrawn from the base of the tower 2 through pipe 40, having pump 41, and is forced either through the heating coil 8, wherein it is raised to a moderate cracking temperature and optionally subjected to cracking, the resulting heated products being either introduced into the soaking drum 39 by way of cross-over pipes 42 and 43, for further cracking, or directly into the evaporator section 35 of tower 3, through transfer line 44; or the liquid residue is passed directly through conduit 45 and cross-over line 43 into the soaking drum 39 for cracking, without previously having traversed the heating coil 8. This last-mentioned alternative method is preferred where the residue has marked coke-forming tendencies such as would tend to make the passage through the heating coil 8 uneconomical.

If desired a trap-out tray 32 may be provided to collect a very heavy, relatively dirty, gas oil condensate which may be recycled to the heating coil 6 by way of pipe line 46 having pump 47. Or this condensate might be collected as mentioned and passed through a separate cracking coil similar to 8 and then be introduced into the evaporator section 35 along with the other stocks. When tray 32 is not used the heavy condensate would pass through heating coil 8 with the residue.

In the combination tower 3 the cracked products undergo separation into vapors and a liquid residue just as described in connection with the action taking place in tower 2. Trap-out trays 47', 48 and 49 perform the same function as corresponding elements 30, 31 and 32 in the tower 2.

The condensates collected on trays 47' and 48 are preferably cracked in the coils 9 and 9' and then introduced into the evaporator section 50 of combination tower 4, soaking drum 51 preferably being furnished for the digestion of the cracked products from coil 9'.

The liquid residue from evaporator section 35 of tower 3 is preferably passed directly through conduits 52, 53 and 54 into the soaking drum 51 for cracking, but alternatively may pass first through the heating coil 10 and then into the drum by way of cross-over line 55, or, as a further alternative, may pass directly through the coil 10 and transfer line 56 into the evaporator section 50 of the tower 4. The condensate collected on trap-out tray 49 may be recycled to the coil 6 through pipe line 57 having pump 58, or may be passed through an individual cracking coil, not shown, into the evaporator section 50 of the tower 4. Trap-out tray 49 may be omitted if desired, in which case the heavy condensate would pass through heating coil 10 with the residue. Reference numerals 59, 60 and 61 indicate pumps for forcing the oils through the cracking coils. Control valves 60', 61, 62, 63, 64 and 65 are provided for the purpose of adjusting pressure conditions. In the combination tower 4 the cracked products separate into vapors and liquid residue, the latter collecting in the base of the tower, while the former pass upwardly through the fractionating section 66 thereof, wherein fractional condensation occurs, one or several reflux condens-

ates being collected, for example two, trap-out trays 67 and 68 being provided for this purpose.

The condensate from trap-out tray 68 may be withdrawn as a distillate fuel, while condensate from tray 67 is preferably recycled to the heating coil 6 through pipe 69, having pump 70. The liquid residue collecting in the base of the tower is withdrawn through draw-off line 71 for sale as fuel oil or for any other desired purpose, or this liquid residue may be flashed in a flashing zone, not shown, and the distillate oil obtained may be returned to the heating coil 6. A further alternative would be to combine the condensates from trays 67 and 68 and subject the mixture to a separate cracking operation in an apparatus, not shown, or more simply, to collect only a single condensate in the fractionator section 66 and subject this to separate cracking.

Distillates of the desired boiling ranges are collected in the receivers 72, 73, 74 and 75, which have cooperating vapor connections 76, 77, 78 and 79, to the towers 1, 2, 3 and 4 respectively, and also, condensers 80, 81, 82 and 83. All or some of these distillates before or after stabilization may be blended to give a distillate of selected characteristics for use as motor fuel or for any other purpose. Connections 84, 85 and 86 are provided so that oil may be withdrawn at these points, or more oil of similar characteristics may be added as desired, to effect balanced operating conditions. Similar connections may be located at corresponding positions adjacent the cracking coils 1, 1', 8, 9, 9' and 10 for like purposes. Various valves shown on the drawing and not indicated specifically by reference numbers are for obvious control purposes.

The necessary reflux lines, cooling coils and heat exchangers for carrying out the various separating and fractionating operations have been omitted in the interest of clarity but the use of these will be obvious to one skilled in the art. Any conventional arrangements for these purposes may be used.

Where the liquid residue is not combined with a cracked intermediate condensate prior to introduction into a following evaporator zone, it may be desirable to provide for the separate withdrawal of individually cracked tars, this being done by introducing the cracked condensate into a separating zone, not shown, wherein vapors separate from liquid residue, only the vapors being passed to the following combination tower, while the liquid residue so separated is withdrawn from the process for any desired purpose, or is subjected to a separate flashing operation to form additional distillate suitable for further cracking in one of the other cracking coils.

From the foregoing description, it will be seen that the residual stock from the initial and each succeeding cracking operation, is subjected to additional cracking, as well as the individual intermediate condensate fractions. This procedure, preferably involving only once-through cracking steps, results in a high yield of high octane number gasoline with a minimum of processing. Each individual type of stock is cracked under the most preferable conditions of temperature and pressure, while at the same time pumping costs are reduced. Through the use of common evaporating and fractionating systems for the several stocks undergoing treatment in the successive stages, the cost of the apparatus required is reduced.

The cracking conditions for carrying out the

several cracking steps may be selected in accordance with the teachings of the prior art and would depend upon the exact stock being cracked and the character of the final desired product.

- 5 Any heavy naphtha cuts, such as removed from trays 14, 30 and 47 may be cracked at temperatures of, for example, 950° F. to 1050° F., more or less, while the clean gas oil cuts such as removed from trays 13, 31 and 48 may be cracked 10 at temperatures in the range of 900° to 975° F. The heavier residual products passing through coils 6, 8 and 10 should be cracked at lower temperatures of, for example, 800°-880° F. to avoid excessive carbon deposition.
- 15 The pressures used may vary widely but it will generally be found preferable to carry out the cracking of the distillate stocks at relatively high pressures of several hundred pounds per square inch, e. g. 700 to 1100 pounds per square inch.
- 20 The residual stocks are most suitably cracked at lower pressures, e. g. 100 to 300 pounds per square inch. When the distillate and residual stocks are cracked together in a common soaking zone, the distillate stock may be heated and partially 25 cracked in the coil at high pressure and then be reduced in pressure for contact with the residual stock in the soaking zone. In the high temperature, high pressure heating coils preferably short times of contact are maintained.
- 30 The heating coils may advantageously be grouped in common furnace settings, so that all of the low-temperature heating and cracking operations are carried out in one furnace, while the higher temperature heating and cracking operations are carried out in one or more separate furnaces. Thus coils 6, 8 and 10 may be in one furnace, 5, 7' and 9' in another furnace, and coils 24, 7 and 9 in a third furnace. Or some or 35 all of the high and low temperature coils may be placed in a single furnace setting, the low temperature coils being mainly in the convection section, and the high temperature coils being mainly in the radiant section.

While I have described a particular embodiment of my invention for the purposes of illustration, it should be understood that various modifications and adaptations thereof may be made within the spirit of the invention as set forth in the following claims.

50 I claim:

1. The process of treating hydrocarbon oil which comprises subjecting heavy oil to distillation to form a condensate fraction and a liquid residue, cracking said condensate and said liquid residue by passing each through a separate heating zone in a stream of restricted cross-sectional area wherein a cracking temperature is attained and conversion occurs, introducing the resulting cracked products into a first separating zone 55 wherein vapors separate from liquid residue, subjecting said vapors to a fractionating operation to form a final desired distillate and a reflux condensate, subjecting said reflux condensate to cracking by passing it through a heating zone in a stream of restricted cross-sectional area wherein said condensate is raised to a cracking temperature and subjected to conversion, combining the resultant stream of hot cracked products with said liquid residue last mentioned and maintaining the combined constituents at a cracking temperature to 60 effect conversion of said liquid residue, introducing cracked products so obtained into a third separating zone wherein vapors separate from liquid residue, and fractionating said vapors last-mentioned to form an additional quantity of final 65 desired light distillate.
- 60 5. A process in accordance with claim 4 wherein during said preliminary distillation step a heavy naphtha condensate is collected and passed through a heating zone in an individual stream of 60 restricted cross-sectional area wherein it is raised to a relatively high cracking temperature sufficient to cause the reformation thereof into products of higher anti-knock value, and the resulting reformed products are introduced into said 65 first separating zone.
- 65 6. The process of treating hydrocarbon oil which comprises subjecting said oil to cracking in a plurality of successive stages, each of which stages includes a heating coil, a reaction chamber, 70 a separator, and a fractionator, the heating coil, reaction chamber, separator and fractionator of each stage being separate, respectively, from those of the other stages, the charge to each cracking coil being a clean condensate stock which, after 75

to form an additional quantity of final desired light distillate.

2. A process in accordance with claim 1 wherein in the fractionation of the vapors separated in said second separating zone lighter and heavier reflux condensates are formed, the lighter reflux condensate constituting the condensate that is passed through said heating zone, and the heavier reflux condensate is combined with said residue first-mentioned for further treatment.

3. A process in accordance with claim 1 wherein in said liquid residue second-mentioned is passed through a heating zone in an individual stream of restricted cross-sectional area wherein the temperature thereof is increased prior to the mixture thereof with said cracked reflux condensate.

4. The process of treating hydrocarbon oil which comprises subjecting crude oil to a preliminary distillation to form a condensate fraction and a liquid residue, separately cracking 20 said condensate and said liquid residue by passing each through a heating zone in a stream of restricted cross-sectional area wherein a cracking temperature is attained and conversion occurs, introducing the resulting cracked products into 25 a first separating zone wherein vapors separate from liquid residue, subjecting said vapors to a fractionating operation to form a final desired distillate and a reflux condensate, subjecting said reflux condensate to cracking by passing it 30 through a heating zone in a stream of restricted cross-sectional area wherein said condensate is raised to a cracking temperature and subjected to conversion, combining the resultant stream of hot cracked products with said liquid residue last 35 mentioned and maintaining the combined constituents at a cracking temperature to effect conversion of said liquid residue, introducing the resulting cracked products into a second separating zone wherein vapors separate from liquid residue, 40 fractionating said vapors to form an additional quantity of final desired light distillate and a reflux condensate, passing said reflux condensate last mentioned through a heating zone in a stream of restricted cross-sectional area wherein 45 it is raised to a cracking temperature and subjected to conversion, combining the resultant stream of hot cracked products with said liquid residue last mentioned and maintaining the combined constituents at a cracking temperature to 50 effect conversion of said liquid residue, introducing cracked products so obtained into a third separating zone wherein vapors separate from liquid residue, and fractionating said vapors last-mentioned to form an additional quantity of final 55 desired light distillate.

5. A process in accordance with claim 4 wherein during said preliminary distillation step a heavy naphtha condensate is collected and passed through a heating zone in an individual stream of 60 restricted cross-sectional area wherein it is raised to a relatively high cracking temperature sufficient to cause the reformation thereof into products of higher anti-knock value, and the resulting reformed products are introduced into said 65 first separating zone.

6. The process of treating hydrocarbon oil which comprises subjecting said oil to cracking in a plurality of successive stages, each of which stages includes a heating coil, a reaction chamber, 70 a separator, and a fractionator, the heating coil, reaction chamber, separator and fractionator of each stage being separate, respectively, from those of the other stages, the charge to each cracking coil being a clean condensate stock which, after 75

being raised to a cracking temperature, is combined with a liquid residue stock and introduced into the reaction chamber, the resulting digested products passing into the separating zone and the charge to the cracking coil in stages following the first, being a condensate stock formed in the fractionator of the preceding stage, and the residue introduced into the reaction chamber with the cracked condensate from the cracking coil last-mentioned, being liquid residue from the separator of the preceding cracking stage, and the final desired product being derived by condensing light fractionated vapors from said fractionators.

15. 7. The process of treating hydrocarbon oil which comprises fractionally distilling in a distilling zone fresh relatively heavy charging stock containing lighter constituents to form a clean condensate cracking stock and an unvaporized residue, simultaneously passing said condensate and said residue through separate cracking zones wherein they are raised to cracking temperatures and subjected to conversion, introducing the resulting cracked products into a first separating zone, separate and apart from said distilling zone, wherein vapors separate from liquid residue, passing the separated vapors into a fractionating zone, also separate and apart from said distilling zone, and fractionally condensing said vapors 20 therein to form a second condensate, passing said second intermediate condensate through a separate cracking zone wherein it is raised to a cracking temperature and subjected to conversion, introducing the resulting cracked products into a second separating zone, separate and apart from said distilling zone, wherein vapors separate from liquid residue, passing the separated vapors into a second fractionating zone, also separate and apart from said distilling zone, and fractionally condensing said vapors last-mentioned therein to form a final desired light distillate and a heavy reflux condensate, and com-

bining said condensate last-mentioned with said unvaporized residue first-mentioned for cracking therewith.

8. A process in accordance with claim 6 where-
in the first stage also includes a second heating 5 coil and the liquid residue stock for the first stage is introduced into said second coil for mild crack-
ing prior to being combined with the clean condensate stock.

9. A process in accordance with claim 6 where-
in the first stage also includes a second heating 10 coil and the liquid residue stock for the first stage is combined with a heavy reflux condensate from the fractionator of the last stage and introduced into said second coil for mild cracking 15 prior to being combined with the clean condensate stock.

10. The process of treating hydrocarbon oil which comprises fractionally distilling fresh rela-
tively heavy charging stock containing lighter 20 constituents to form a clean condensate cracking stock and an unvaporized residue, simultane-
ously passing said condensate and said residue through separate cracking zones wherein they are raised to cracking temperatures and subjected 25 to conversion, introducing the resulting cracked products into a first separating zone wherein vapors separate from liquid residue, fractionally condensing said vapors to form a second condensate, passing said second condensate and said 30 residue last mentioned through separate cracking zones wherein they are raised to cracking tem-
peratures and subjected to conversion, introduc-
ing the resulting cracked products into a second 35 separating zone wherein vapors separate from liquid residue, fractionally condensing said vapors last-mentioned to form a final desired light dis-
tillate and a heavy reflux condensate, and com-
bining said condensate last-mentioned with said unvaporized residue first-mentioned for cracking 40 therewith.

MAURICE H. ARVESON.
